ELECTRICAL COMPENSATOR.

1,344,742.

Specification of Letters Patent. Patented June 29, 1920.

Application filed August 9, 1916. Serial No. 113,890.

To all whom it may concern:

Be it known that I, ALLEN A. TIRRILL, a citizen of the United States, and a resident of Pittsburgh, in the county of Allegheny and State of Pennsylvania, have invented a new and useful Improvement in Electrical Compensators, of which the following is a specification.

My invention relates to compensators whereby voltage regulators and other devices may be caused to respond, in their operation, to the voltage obtaining at a distant point in an electrical distributing circuit.

When it is desired to have a potential regulator for an electrical generator operate to maintain the voltage at a distant point of the connected circuit substantially uniform, it is customary to employ a compensator which renders the regulator responsive, in operation, to the voltage obtaining at the distant point. The compensator usually comprises a resistance element and an inductance element that receive current through a current-transformer. The current is proportional to that traversing the circuit and its value is adjusted to be approximately in the same ratio as the resistance and inductance of the line. The connections are so arranged that the counter-electromotive forces set up in the resistance and inductance elements serve to reduce the voltage applied to the regulator winding or windings by an amount proportional to the drop in voltage in the line to the distant point.

When one or several lines are supplied from bus-bars, the current transformer that supplies the resistance and inductance elements of the compensator should be placed where it will be traversed by the total current delivered to the line or lines. However, this is often subject to disadvantages, especially when the voltage of the lines is high, and it is the object of the present invention to provide compensating means that may be employed in connection with the low-tension sides of the transformer or transformers that supply high-tension current to the bus-bars to which the several lines are connected, the arrangement being such that the compensation may be substantially correct, irrespective of the number of transformers and power-distributing lines in use.

In the single figure of the accompanying drawing, which diagrammatically illustrates a system embodying my invention, the main circuits are illustrated by single lines for the sake of simplicity, it being understood that the single lines are intended to represent a plurality of conductors necessarily employed to form an electrical circuit. The system comprises a set of high-tension bus-bars 1, from which a plurality of distributing or transmission lines 2, 3, and 4 are supplied and to which high-tension current is supplied through a plurality of banks of voltage changing-transformers 5, 6 and 7, the primary windings of which are connected to a set of low-tension bus-bars 8. Switches 9 are employed for selectively connecting lines 2, 3 and 4 to the high-tension bus-bars 1, and switches 10 and 11 are employed for selectively connecting the transformers 5, 6 and 7 between the high-tension and low-tension bus-bars. The low-tension bus-bars receive current from one or more generators having armatures 12 and field-magnet windings 13 that receive current from exciter bus-bars 14 and 15. An exciter, having an armature 16 and a field magnet winding 17, supplies current to the bus-bars 14 and 15. The voltage of the exciter is governed by a relay 18 that is adapted to open and close a circuit in shunt to a resistor 19 connected in series with exciter field-magnet winding 17.

The relay 18 is provided with an energizing winding 22 that receives current from the exciter, or from any other suitable source and is periodically short circuited by the engagement and disengagement of a pair of stationary and movable contact terminals 23 and 24 that constitute elements of the main control element of a vibrating-contact regulator. The regulator comprises also a bell-crank lever 25 having a stationary fulcrum at 26 and providing a fulcrum at 27 for another lever 28 that is provided with an upwardly and laterally extending arm 29 upon which the movable contact terminal 24 is mounted. The lever 25 is actuated by an electro-magnet having a winding 30 that receives current from the low-tension bus-bars 8 through a transformer 31. In circuit with the winding 30 is a resistor 32 a portion of which is periodically short circuited by a relay 33 having an energizing winding 34 that is connected in par-

allel with the relay winding 22. The current flow through the winding 34 is controlled by the contact terminals 23 and 24 in the same manner as that through the 5 winding 22. The engagement and disengagement of the contact members of the relay 33 causes the degree of energization of winding 30 to vary, with the result that the lever 25 is vibrated and the contact terminal 24 is moved into and out of engagement 10 with the stationary terminal 23.

The lever 28 is actuated by an electromagnet having a winding 36 that receives current from the bus-bars 8 through the 15 transformer 31 and also through two resistors 37 and 38 and two inductive-resistance elements 39 and 40 that constitute parts of the compensator whereby the voltage of the secondary winding of the transformer 31 may be compensated or reduced 20 in proportion to the drop in voltage in the lines 2, 3 and 4 and in the transformers 5, 6 and 7.

The compensator also comprises current-transformers 41 and 42 associated with each 25 set of connections between the low-tension bus-bars 8 and the several voltage-changing transformers 5, 6 and 7. Instead of employing two entirely separate and distinct 30 transformers in association with each set of connections, it will, of course, be understood that a single transformer having two secondary windings may be employed. The secondary windings of the transformers 41 35 are connected in parallel with each other and to the primary winding 43 of a totalizing transformer 44. The secondary winding of the transformer 44 has its terminals connected, respectively, to suitable points 40 in the resistor 37 and in the inductive element 39. Likewise, the secondary windings of the transformers 42 are connected in parallel with each other and to the primary winding of another totalizing transformer 45 46. The terminals of the secondary winding of the transformer 46 are connected to suitable points in the resistor 38 and in the inductive element 40.

The values of the ohmic and inductive 50 resistances of the devices 37 and 39 are so adjusted as to bear approximately the same ratio to each other as that of the ohmic and inductive resistances of the lines 2, 3 and 4, and the values of the ohmic and inductive resistances of the devices 38 and 40 are so adjusted as to bear approximately the same ratio to each other as that of the ohmic and inductive resistances of the 55 transformers 5, 6 and 7. The transformation 60 ratios of the transformers 44 and 46 are both adjustable, as, for instance, by the provision of suitable taps in their primary windings and movable switch arms 47 and 48 that are adapted to make connections to 65 the taps. When all of the transformers and

all of the lines are in use, the switch arms occupy the positions shown, and, when only one transformer and only one line are in use, the arms should occupy positions shown in broken lines. The arm 47 is adjusted to 70 correspond to the number of lines in use and the arm 48 to correspond to the number of transformers in use. The movements of the arms 47 and 48 may be effected manually, or they may be effected by any suitable 75 means at present available and not constituting part of the present invention. It will be understood that any number of transformers may be used between the low-tension and high-tension bus-bars and, likewise, any number of distributing circuits 80 may be connected to the bus-bars 1.

The regulator performs its usual functions and, since, *per se*, it constitutes no part of the present invention, it is unnecessary 85 to describe its operation in detail. The movable arms 47 and 48 are adjusted in position to correspond, respectively, to the number of lines and to the number of banks of transformers in use, and, when this is 90 done, the current traversing the regulator winding 36 is proportional to the voltage of the bus-bars 8 minus a voltage proportional to the drop in voltage in the transformers and lines in use. In other words, 95 the voltage impressed upon the winding 36 is proportional to the voltage obtaining at distant points of the lines 2, 3 and 4, irrespective of the character and size of the loads. 100

I claim as my invention:

1. In an electrical system, the combination with a plurality of voltage-changing transformers, a plurality of feeder circuits, and selective switching means associated, 105 respectively, with the transformers and the feeder circuits, of current-transforming means associated, respectively with the connections to the voltage-changing transformers and comprising two sets of parallel-connected secondary windings, totalizing transforming means having two primary windings associated, respectively, with the said sets of secondary windings, resistance and inductance elements to which the totalizing transforming means supplies current, and an instrument having a winding the circuit of which includes the said resistance and inductance elements. 110

2. In an electrical system, the combination 120 with a plurality of voltage-changing transformers, a plurality of feeder circuits, and selective switching means associated, respectively, with the transformers and the feeder circuits, of current-transforming 125 means associated, respectively, with the connections to the voltage-changing transformers and comprising two sets of secondary windings, totalizing transforming means having two primary windings associated, 130

respectively, with the said sets of secondary windings, resistance and inductance elements to which the totalizing transforming means supplies current, and an instrument 5 having a winding the circuit of which includes the said resistance and inductance elements.

3. In an electrical system, the combination with a plurality of voltage-changing transformers, a plurality of feeder circuits, and selective switching means associated, respectively, with the transformers and the feeder circuits, of current-transforming means associated, respectively, with the connections to the voltage-changing transformers and comprising two sets of secondary windings, resistance and inductance elements to which the said secondary windings deliver current, and an instrument having a 15 winding the circuit of which includes the said resistance and inductance elements.

4. In an electrical system, the combination with a plurality of voltage-changing transformers, a plurality of feeder circuits, 25 and selective switching means associated, respectively, with the transformers and the feeder circuits, of current-transforming means associated, respectively, with the connections to the voltage-changing transformers and comprising two sets of secondary windings, an instrument having a winding, and means for developing a counter-electromotive force in circuit with the instrument winding and supplied with current from 35 said secondary windings.

5. In an electrical system, the combination with two sets of bus-bars, a plurality of voltage-changing transformers, means for connecting the same between the bus-bars, a 40 plurality of feeder circuits, and means for connecting them to one set of the bus-bars, of current transforming means associated, respectively, with the connections to the voltage-changing transformers and comprising two sets of parallel-connected secondary windings, a variable-ratio totalizing transformer associated with each set of said secondary windings, two sets of resistance and inductance elements to which the totalizing 45 transformers supply current, and an instrument having a winding the circuit of which includes the said resistance and inductance elements.

6. In an electrical system, the combination with a voltage-changing transformer, a feeder-circuit, and connectors associated with the transformer and feeder-circuit, of a current transformer inserted in circuit 55 with the connectors to the voltage-changing transformer and comprising two secondary windings, a totalizing transformer having two primary windings associated, respectively, with said two secondary windings, resistance and inductance elements severally 60 connected to said totalizing transformer

windings, and an instrument having a winding the circuit of which includes the resistance and inductance elements.

7. In an electrical system, the combination with a supply circuit, voltage transformer means, and a plurality of feeder circuits connected through the transformer means to the supply circuit, of means comprising a number of parallel-connected series transformers for automatically regulating the supply-circuit voltage in accordance with the condition of the feeder circuits connected to the supply circuit to maintain constant voltage conditions on the 70 feeder circuits.

8. In an electrical system, the combination with a supply circuit, a plurality of feeder circuits, a plurality of voltage transformers, and means comprising switches for selectively connecting the feeder circuits 75 through the voltage transformers to the supply circuit, of current-transforming means associated with said connecting means, automatic means controlled by said current-transforming means for regulating the supply-circuit voltage in accordance with the condition of the feeder circuits, and means for adjusting said automatic means in accordance with the number of feeder circuits 80 and voltage transformers in circuit.

9. In an electrical system, the combination with a supply circuit, a plurality of feeder circuits, a plurality of voltage transformers, and means comprising switches for selectively connecting the feeder circuits through 90 the voltage transformers to the supply circuit, of current-transforming means associated with said connecting means, automatic means controlled by said current-transforming means for regulating the supply-circuit voltage in accordance with the voltage obtaining at the ends of the selected 95 feeder circuits, and means for adjusting said automatic means in accordance with the number of feeder circuits and voltage transformers in circuit.

10. In an electrical system, the combination with a supply circuit, a plurality of feeder circuits, a plurality of voltage transformers, and means for connecting the 100 feeder circuits through the voltage transformers to the supply circuit, of two sets of parallel-connected series transformers associated with said connecting means, and means connected to said current transformers for regulating the supply-circuit voltage in accordance with feeder-circuit conditions.

11. In an electrical system, the combination with a supply circuit, a plurality of feeder circuits and means comprising switches for selectively connecting the feeder circuits to the supply circuit, of current-transforming means associated with 125 said connecting means, and means connected 130

to said current-transforming means for regulating the supply-circuit voltage in accordance with the voltage obtaining at the ends of the feeder circuits.

5. 12. In an electrical system, the combination with a supply circuit, a plurality of feeder circuits and means comprising switches for selectively connecting the feeder circuits to the supply circuit, of current-
10 transforming means associated with said connecting means, and means associated with said current-transforming means for regulating the supply-circuit voltage in accordance with the condition of the feeder circuits connected to the supply circuit.
15. 13. In an electrical system, the combination with a supply circuit, a plurality

of feeder circuits, a plurality of voltage transformers, and means comprising switches for selectively connecting the 20 feeder circuits through said transformers to the supply circuit, of current-transformer means associated with said connecting means and means connected to the transformer means for regulating the supply-circuit 25 voltage in accordance with the condition of the voltage transformers and the condition of the feeder circuits that are connected to the supply circuit.

In testimony whereof, I have hereunto 30 subscribed my name this 21st day of July, 1916.

ALLEN A. TIRRILL.
